AUTOMOBILE

Gian Paolo Boano, Turin, Italy, assignor to Fiat
Societa per Azioni, Turin, Italy

Filed Mar. 29, 1972, Ser. No. 239,399

Claims priority, application Italy Oct. 8, 1971

Term of patent 14 years

Int. Cl. D12—08

U.S. Cl. D12—91

FIG. 2

FIG. 3

FIG. 4

FIG. 6

FIG. 7

FIG. 1 is a right side elevational view of an automobile showing my new design;

FIG. 2 is a top plan view thereof, with the windshield wipers shown in an alternate arrangement;

FIG. 3 is a front elevational view thereof;

FIG. 4 is a rear elevational view thereof;

FIG. 5 is a left side elevational view thereof;

FIG. 6 is a rear elevational view of an automobile showing a second embodiment of my new design, which differs from the first embodiment in the configuration of the front and rear as shown in FIGS. 6 and 7, respectively; and

FIG. 7 is a front elevational view of FIG. 6.

I claim:

The ornamental design for the automobile, as shown.
